APPARATUS FOR CANNING FOODSTUFFS

John Mills, Brooklyn, N. Y., assignor, by mesne assignments, to The Crown Cork and Seal Company, Inc., New York, N. Y., a corporation of New York

Application July 14, 1933, Serial No. 680,456

14 Claims. (Cl. 99—251)

This invention relates broadly to machines for sterilizing canned food products and contemporaneously sealing the containers therefor and more specifically to improvements in the structure of the valve header for such machines. The invention further contemplates an improved and more efficacious method of processing canned foods.

In my co-pending application, Serial No. 10 629,678, filed August 20, 1932, and entitled "Apparatus for food processing" a sterilizing and can sealing machine of the continuous operating type is disclosed which comprises generally a rotatively driven drum or turret constructed to progressively receive a plurality of cans which, prior to delivery thereto have been filled with an edible. During the operation of the machine these cans are brought into engagement with the valve header where fluid communication with the interior of the can is effected. In the early portion of the operating cycle of the turret a partial vacuum is created in the valve header which causes the rarefaction of the gases within the can. In the later portion of the operating cycle 15 of the turret steam under pressure is injected into the cans which causes the contents thereof to be violently agitated and heated to a relatively high temperature. In my co-pending application aforesaid, the mechanism provided to exhaust the 20 air from the cans was connected to a manifold, common to the steam exhaust line, and formed with conduits which led to each of the valve headers. Steam lines were also connected with each of the headers and exhaust lines led therefrom to an exhaust manifold. The structure further embodied control cams and operating linkage which was organized to successively actuate steam and vacuum valves within the headers and govern the period during which each of the valves was 25 retained in its open position.

In the present invention, which is an improvement over my former application, Serial No. 629,678, a partial vacuum is automatically created within each of the headers upon the adjustment of an exhaust steam valve associated therewith. Thus, the vacuum valves heretofore employed, the unit for creating a vacuum, the conduits therefor and the operating linkage may all be eliminated from the machine thereby effectuating a more efficient evacuation of air from the can, greater expedition of operation and material economy in the production and erection of the machine.

In the drawings which illustrate the preferred 55 embodiment of the invention—

Figure 1 is a front elevational view of a sterilizing and container sealing machine embodying the improved valve header.

Figure 2 is a fragmentary sectional view, partially in elevation, the section being taken on a plane indicated by the line 2—2 in Figure 1.

Figure 3 is a fragmentary elevational view of the machine including the arrangement of the valve header, the conduit connections and control linkage therefor.

Figure 4 is a detailed view in section illustrating the structure of the improved valve header.

Referring to Figure 1 the sterilizing machine comprises generally a base or pedestal 10 having a rotatively driven drum or turret 11 journalled 15 thereon upon which there is mounted a plurality of valve headers 12 disposed in radial alignment with a series of can chucking platforms 13 which are arranged upon the outer face of the turret 11 adjacent the periphery thereof.

The turret 11 is driven by a pinion 14 intermeshed with a gear 15 formed in the periphery of the turret and, as disclosed in my former application, Serial No. 629,678, is provided with mechanism to effect the continuous delivery of cans thereto. The drum or turret 11 is mounted upon a tubular shaft 16 journalled in bearings (not shown) in the pedestal 10. Within the shaft 16 there is a tube 17 affixed against rotation to the base or pedestal 10. The outer end of the tube 17 is connected to the steam exhaust line which communicates with a condenser preferably disposed remote from the machine. The inner end of the tube 17 is formed with a flange 18 upon which there is mounted a disc 19 having a radially enlarged cam in the periphery thereof. Within the inner end of the tube 17 there is a conduit 20 having an enlarged head 21, which is provided with a cover plate 22 apertured to receive a pipe 23 communicating with the source of steam supply.

As indicated in Figure 2 a stuffing box 24 is provided upon the conduit 20 to prevent escape of the exhaust steam from the connection between the conduit 20 and the tube 17. Packing is also provided about the pipe 23 to seal the connection between the pipe and the flange 22. The head 21 is constructed with a shouldered recess therein which is divided by a plate 26 forming chambers 27 and 28. The outer chamber 27 constitutes a steam chest to which conduits 29, leading to the valve headers 12, are connected. The inner chamber 28 communicates with the tube 17 and receives the conduits 30 which lead

from the steam exhaust ports in the valve headers.

During the operating cycle of the machine cans A filled with an edible are successively delivered upon the chucking platforms 18 where they are elevated into abutting engagement with the valve headers 12. The retraction of the can from the header occurs near the completion of the turret cycle and is effected by the engagement of arms 31 upon the platform guides 32 with a fixed ledge or track cam 33.

The can A employed in conjunction with the apparatus herein illustrated and disclosed in connection with my co-pending application is formed with a valve disc a which is engageable with a valve stem 34 subtended from the header 12. When the valve stem 34 engages the disc a the head 35 of the valve will be lifted from its seat, the disc a depressed and steam delivered through the conduit 29 to the interior of the header will be admitted through the valve into the can A.

The valve headers embodying the present invention comprise a housing having a chamber 36 therein with which the steam inlet 29, the exhaust line 30 and the valve 35 communicate. The base of the header is constructed to receive a valve guide 37 recessed adjacent its outer end to receive a gasket 38 which is provided to afford a seal between the header and the can during the evacuating and sterilizing cycle of the turret. Within the chamber 36 adjacent the steam inlet 29 there is a jet 39 having the outer end thereof extended within a Venturi tube 40 which is mounted in the end wall of the header coaxial with the inlet port of the conduit 29. The outer end of the Venturi tube 40 is extended within a valve cage 41 affixed to the body of the header 12. The valve cage may be formed to receive any suitable type of valve, such for instance as the slide valve 42 illustrated herein. In this embodiment the core 43 is provided with a transverse bore 46 which is disposed to facilitate fluid communication between the Venturi tube and the exhaust port upon reciprocative adjustment of the core. The valve core 43, as illustrated herein, is reciprocal by linkage comprising a bell crank 45 pivotally supported upon a bracket 46 formed in the valve cage 41. The lower arm of the bell crank 50 is slotted to receive a pin 47 retained within the shank of the valve core 43. The upper arm of the bell crank is cupped to retain a push rod 48 which is supported in a recess in the end of a lever 49 fulcrumed intermediate its end upon a stud 50 mounted upon the drum 11. A tension spring 51 is secured to the outer end of the lever 49 to effect the retention of the valve in its closed position. Upon the outer end of the lever 49 there is a roller 52 mounted for engagement with the disc cam 19. The periphery of the cam 19 is formed with a land 53 of suitable radial height to cause adequate lever movement to shift the valve core to its open position. The disposition of the land, in relation to the turret, is arranged to open the valve during the initial rotative cycle of the turret. The circumferential length of the land 53 is formed to maintain the valve in its open position through approximately the first 90° travel of the turret.

In the cyclic operation of the machine, after a can has been delivered to the chucking platform of the turret it is elevated into abutting relation with the valve header where the valve stem 34 depresses the disc a, lifts the valve head 35 from its seat and thus effects fluid communica-

tion between the header chamber 36 and the interior of the can. At this time the land 53 of the can 16 is positioned to cause the opening of the valve 42 so that steam emitted from the jet 39 will flow through the Venturi tube and be exhausted through the line 30. As the steam rushes through the Venturi tube a vacuum of approximately 24 to 29 cubic inches of mercury is created within the chamber 36, and since the interior of the can is in fluid communication therewith the gases within the can A are highly rarefied. When the turret has revolved through the evacuating portion of its cycle the roller 52 will have reached the smaller diametric section of the cam 19 thus causing movement of the control linkage and the closure of the valve 42. The steam admitted through the conduit 29 will then flow through the valve 35 and thus effect the sterilization of the contents of the can A. Upon completion of the sterilizing cycle of the turret the can will be oscillated into position for application of the sealing mechanism, as described in my co-pending application aforesaid. The area of the head of the valve 35 is greater than the valve port so that the steam pressure within the chamber 36 will cause the immediate closure of the valve when the engagement of the valve stem with the can is broken upon removal of the can from the header.

Although the foregoing description is necessarily of a detailed character, in order that the invention may be completely set forth, it is to be understood that the specific terminology is not intended to be restrictive or confining, and that various rearrangements of parts and modifications of structural detail may be resorted to without departing from the scope or spirit of the invention as herein claimed.

I claim:

1. A valve header comprising a housing having a chamber therein, an inlet communicating with said chamber, a tube constituting an exhaust steam passage, a jet connected with said inlet and extended within said tube, a valve within said chamber, a valve stem therefor extended beyond said housing and adapted to open said valve when engaged with an extraneous object and a second valve disposed in the exhaust steam passage beyond said tube for controlling the egress of steam therethrough.

2. A valve header comprising a housing having a chamber therein, an inlet communicating with said chamber, a Venturi tube, a valve cage having an exhaust steam passage therein, a jet connected with said inlet and extended within said Venturi tube, a poppet valve within said chamber and having the stem therefor extended beyond the housing, and a valve disposed within the exhaust steam passage beyond said Venturi tube for controlling the discharge of steam through said exhaust steam passage.

3. A valve header comprising a housing having a chamber therein, an inlet communicating with said chamber, a Venturi tube, a valve cage having an exhaust steam passage therein, a steam jet connected with said inlet and extended within said Venturi tube, a valve in said chamber adapted for external control, and a valve in said exhaust steam passage for controlling the egress of steam therethrough.

4. In a machine for sterilizing and sealing canned food products embodying a frame having a drum rotatively mounted thereon, a valve header, a steam inlet conduit connected thereto, an exhaust steam conduit connected to said header

a valve in said exhaust steam conduit, mechanism coordinated with said drum for controlling the operation of said valve during the rotative cycle of said drum, mechanism on said drum for supporting a can in abutting engagement with said header, a valve in said header for effecting communication between the header and the can, and means within said header for creating a partial vacuum therein upon adjustment of said exhaust steam valve.

5. In a machine for sterilizing and sealing canned food products, embodying a frame having a drum rotatively mounted thereon, a valve header, a steam inlet conduit connected thereto, an exhaust steam conduit connected to said header, a valve in said exhaust steam conduit, mechanism on said drum for supporting a can in abutting engagement with said header, a valve in said header for effecting communication between the header and the can, a Venturi tube within said header intermediate the interior thereof and the steam exhaust conduit, a jet connected to said steam inlet and extended within said Venturi tube, a non-rotatable cam, linkage coordinated with said cam for opening the exhaust steam valve during the rotative cycle of said drum, a can supporting mechanism on said drum for maintaining the can in abutting engagement with said header, and a valve in said header for effecting communication between the interior of the can and the interior of the header.

6. In a machine for sterilizing and sealing canned food products embodying a frame having a drum rotatively mounted thereon, a valve header, a steam inlet conduit connected thereto, an exhaust steam conduit connected to said header, a valve in said exhaust steam conduit, mechanism on said drum for supporting a can in abutting engagement with said header, a valve in said header, a valve stem therefor arranged to effect the opening of said valve when engaged with said can, and means within said header comprising a Venturi tube and a steam jet for creating a partial vacuum upon adjustment of said exhaust steam valve.

7. In a machine for sterilizing and sealing canned food products embodying a frame having a drum rotatively mounted thereon, a valve header, a steam inlet conduit connected thereto, an exhaust steam conduit connected to said header, a valve in said exhaust steam conduit, a cam disc non-rotatively mounted upon said frame, a lever mounted upon said drum and having an end thereof engageable with the periphery of said disc cam, linkage operatively connecting said lever with said valve, a valve in said header adapted to effect communication to the interior of said header, and means within said header to create a partial vacuum therein upon the opened adjustment of the exhaust steam valve and the header valve.

8. In a machine for sterilizing and sealing canned food products embodying a frame having a drum rotatively mounted thereon, a valve header, a steam inlet conduit connected thereto, an exhaust steam conduit connected to said header, a valve in said exhaust steam conduit, a cam affixed to said frame linkage mounted upon said drum and operably associated with said cam and said valve, the surface of said cam being formed to effect the actuation of the valve during an operating cycle of said drum, a valve in said header for effectuating communication between the header and the contents of said canned food products being processed by said machine, and means within said header for producing a partial

vacuum when the first and last named valves are opened.

9. A valve header comprising a housing having a chamber therein, an inlet communicating with said chamber, a Venturi tube, a valve cage having an exhaust steam passage therein, a jet connected with said inlet and extended within said Venturi tube, a poppet valve within said chamber and having the stem therefor extended beyond the housing for engagement with an extraneous object to hold the valve in its open position, the head of said poppet valve being of greater area than the seat therefor to provide for the closure of the valve by steam pressure within the chamber when the exhaust steam passage is closed and the valve stem is free of engagement with an extraneous object.

10. In a machine for sterilizing and sealing canned food products embodying a frame having a drum rotatively mounted thereon, a valve header, a steam inlet conduit connected thereto, an exhaust steam conduit connected to said header, a valve in said exhaust steam conduit, mechanism on said drum for supporting a can in abutting engagement with said header, a valve in said header, a valve stem therefor arranged to effect the opening of said valve when engaged with said can, means within said header comprising a Venturi tube and a steam jet for creating a partial vacuum upon adjustment of said exhaust steam valve, the area of the head of said header valve being proportioned in relation to the valve seat to cause the steam pressure within the chamber to close the valve when the valve stem is disengaged with the can.

11. Apparatus for canning food stuffs including a turret rotatable about a horizontal axis and provided with a fixed, container-supporting means rotatable therewith, a header having a nose portion engageable with the valve part of a valved container supported on said means, said header having a chamber, inlet and outlet passages communicating therewith and a nose passage extending from the chamber thru the nose portion of the header, the outlet passage including a Venturi portion, valve means in the nose passage operable to open the valve of a container on said supporting means and thereby to connect the interior of the container with the chamber of the header, a conduit for conducting steam under pressure to said inlet passage, and a valve associated with said outlet passage and open during part of the rotation cycle of said turret and container-supporting means and while said nose passage is open, whereby the passage of steam at a high velocity through said chamber will cause gases to flow from said container and chamber thru said outlet passage.

12. Apparatus for canning food stuffs including a turret rotatable about a horizontal axis and provided with a fixed, container-supporting means rotatable therewith, a header having a nose portion engageable with the valve part of a valved container supported on said means, said header having a chamber, inlet and outlet passages communicating therewith and a nose passage extending from the chamber thru the nose portion of the header, the walls which form the inlet passage being extended to a point within the walls defining said outlet passage, valve means in the nose passage operable to open the valve of a container on said supporting means and thereby to connect the interior of the container with the chamber of the header, a conduit for conducting steam under pressure to said inlet passage, a valve in the outlet

passage of said header, and means associated with said valve to open said valve during part of the rotation cycle of said turret and container-supporting means, whereby the passage of steam at 5 high velocity through said inlet and outlet passages will cause gases to flow from said chamber thru said outlet passage.

13. Apparatus for canning food stuffs including a turret rotatable about a horizontal axis and 10 provided with a fixed, container-supporting means rotatable therewith, a header having a nose portion engageable with the valve part of a valved container supported on said means, said header having a chamber, inlet and outlet pas- 15 sages communicating with the chamber at aligned, oppositely disposed points so that steam under pressure may pass straight across the chamber from the inlet to the outlet passage, said outlet passage being formed as a venturi, and a 20 nose passage extending from the chamber thru the nose portion of the header, valve means in the nose passage operable to open the valve of a container on said supporting means and thereby to connect the interior of the container with the 25 chamber of the header, a conduit for conducting steam under pressure to said inlet passage, a valve associated with the said outlet passage and operable during part of the rotation cycle of said turret and container-supporting means to permit 30 steam to flow from said inlet passage across said chamber and out thru said outlet passage while the nose passage is open.

14. Apparatus for canning food stuffs including a turret rotatable about a horizontal axis, a plurality of container-supporting means rotatable with and radially disposed on said turret, a plurality of headers rotatable with the turret and disposed thereon radially inward from said container-supporting means, each header having a nose portion engageable with the valve part of a valved container supported on the adjacent container-supporting means, each header having a 10 chamber, inlet and outlet passages communicat- 15 ing therewith, and a nose passage extending from the chamber thru the nose portion of the header, the adjacent ends of the said inlet and outlet passages being close to but spaced apart from each other in said chamber valve means in the nose passage operable to open the valve of a container on the adjacent supporting means and thereby to connect the interior of the container with the chamber of the header, conduits for conducting 20 steam under pressure to the inlet passages of each header, and valves associated with each of said outlet passages, each such valve being opened during part of the rotation cycle of said turret and while the respective nose passage is open, where- 25 by passage of steam at high velocity from the inlet passage to the outlet passage will cause gases to flow from the said chamber and container to said outlet passage.

JOHN MILLS. 30
